UNITED STATES PATENT OFFICE.

WILLIAM C. LIKLY AND JOHN J. CANNAN, OF ROCHESTER, NEW YORK, AS-SIGNORS TO HENRY LIKLY & COMPANY, OF ROCHESTER, NEW YORK, A CORPORATION OF NEW YORK.

GARMENT-SUPPORT FOR TRUNKS.

No. 851,535.

Specification of Letters Patent.

Patented April 23, 1907.

Application filed May 14, 1906. Serial No. 316,626.

To all whom it may concern:

Be it known that we, WILLIAM C. LIKLY and JOHN J. CANNAN, both of Rochester, in the county of Monroe and State of New York, have invented certain new and useful Improvements in Garment-Supports for Trunks; and we do hereby declare the following to be a full, clear, and exact description of the same, reference being had to the accompanying drawings, forming a part of the specification, and to the reference-numerals marked thereon.

Our present invention relates to baggage and particularly to that class known as wardrobe trunks in which garments are suspended within a chamber or compartment, and it has for its object to provide a movable supporting frame which is capable of being drawn outwardly, to afford access to the garments to facilitate packing them and to permit their removal, together with means for supporting the outer end of the frame, when it is drawn forward, to prevent the weight of the suspended garments from straining it, as well as to prevent the trunk from tipping forwardly.

To these and other ends the invention consists in certain improvements and combinations of parts all as will be hereinafter more fully described, the novel features being pointed out in the claims at the end of the specification.

In the drawings: Figure 1 is a vertical sectional view of a trunk constructed in accordance with our invention, showing the cover or door in a closed position. Fig. 2 is a similar view, the door or cover being open and the supporting frame shown in the extended position. Fig. 3 is a horizontal sectional view taken on the line 3^x 3^x of Fig. 2. Fig. 4 is a detail front elevation of the upper end of the trunk body showing the supporting frame therein, and

Similar reference numerals in the several figures indicate similar parts.

In illustrating the present invention we have shown a trunk of the usual construction consisting of the rectangular box or body having a top 1, a bottom 2, a back 3 and the two sides 4. Hinged at one side of the box, or body, is a door, or cover, comprising a panel 5, sides 6 and ends 7 which latter are adapted to cooperate with the corresponding sides

and ends of the box, or body, and when closed thereon to be secured by the usual or any preferred construction of hasps or locks (not shown). The trunk is adapted to rest upon its end 2 which is provided with casters or rollers 8 to facilitate its being readily moved when supported in the normal position, as shown in Figs. 1 and 2, and a similar roller 8' is provided on the corresponding end of the door. On each end of the trunk are the handles by means of which it may be carried.

The box or body forms a chamber constituting a wardrobe compartment, at the upper end of which in proximity to the top 1 is arranged a supporting frame mounted in ways or channels formed in guides 10, attached to the sides 4 of the body in proximity to the end 1, on which it is capable of being moved outwardly from the position shown in Fig. 1 to that shown in Fig. 2. The frame may be constructed in any desired manner, but the form which we find in practice to be preferable comprises side pieces or rails 9, connected at their forward ends by a cross piece, or bar, 11 and at their rear ends by a similar bar 12. Extending longitudinally of the frame and arranged centrally thereon is a rod 13, the ends of which extend through perforations in the cross pieces 11 and 12 and are secured to the latter by nuts 14 and 15. This bar forms a support on which a plurality of garment hangers 16 are arranged which are adapted to receive the larger articles of wearing apparel, such as coats, overcoats, vests, trousers or dresses. Depending from the rear end of the supporting frame is a follower comprising the side pieces 17 and 18 connected at intermediate points by slats 19. Cooperating with this follower is a second one, indicated by 20, which is movable longitudinally on the bar 13, being suspended from a ring 21 thereon by a detachable snap 22. The movable follower forms a compressor by means of which the garments supported upon the hangers 16 may be firmly secured in the trunk during transportation and to hold it in contact with the garments a plurality of straps 24 are employed which are adapted to surround both the stationary and the movable followers. This arrangement of the parts possesses the advantage in that the garments may be folded

smoothly and their respective hangers moved rearwardly on the frame, as successive garments are added, and when the desired number have been placed on the frame they may 5 be compressed before the frame is moved inwardly, while in an accessible position outside of the trunk, thus preventing their folds from being shaken out during the inward movement of the frame. Two or more of 10 the straps 24 are employed for moving the follower frames relatively and these are held loosely on the rear or stationary follower by cleats 25. To support their free ends, which project outwardly from the trunk body, 15 when disengaged from the movable follower, spring clips 26 are provided which are preferably located on the vertical edges of the sides 4—4 so that the straps may be readily inserted in them and supported so that during 20 the packing operations they will not become inaccessible by falling in rear of the garments. A strap 24^a is secured to the interior of the trunk at about the center thereof and its ends are adapted to be united in front of the follower or compressor 20, after the garment supporter frame is moved inwardly to securely hold it within the trunk.

The ends of the stationary guides 10 project outwardly beyond the open side of the 30 box or body of the trunk, and the forward edge of the supporting frame, formed by the piece 11, extends transversely between them, across the entire width of the open side of the body, and the side and end walls 6 and 7 of the cover are of sufficient depth to receive these parts when it is in the closed position. The frame, when it is drawn outwardly, to the position shown in Figs. 2 and 3, is supported by a strut 27 having an enlarged lower 35 end provided with a rubber tip 28 adapted to rest upon the floor in front of the trunk. The upper end of the strut is movably connected to the supporting frame by means of a guide along which it may be moved to elevate it out of engagement with the floor and in position to be carried into the wardrobe compartment. The guide is illustrated in the present instance as a rod 29 having a forward end 30, extending laterally beneath the 40 forward edge of the frame, and provided with a foot 31 by means of which it is connected by securing devices, to the lower side of the cross piece 11. The other end of the rod extends rearwardly and upwardly above 45 the bottom of the frame, as indicated at 32, in proximity to and parallel with one of the side pieces 9, to which it is connected by securing devices passing through perforations in the foot 33. The connection between the 50 guide and the strut 27 is made by providing the latter with an eye 34. By this arrangement it will be seen that as the strut is moved rearwardly into the inoperative position it will also be elevated a sufficient distance to 55 carry its lower end above the upper face of

the bottom 2 of the trunk, permitting it to pass therein. By extending the guide along one side of the trunk, and curving it downwardly and laterally beneath the frame the strut, when in the operative position, may be 70 located centrally thereof, and when in the inoperative position, it is supported at the side of the frame so as not to interfere with the garments, or the garment hangers, depending therefrom. To prevent the strut 75 from moving when it is within the trunk, the laterally extending portion 35 of the guide, in proximity to the foot 33, is carried downwardly, or offset, so that when the eye 34 is passed thereon, the lower end of the strut will 80 rest upon the bottom of the trunk. The movement of the eye into this part of the rod will cause it to be rotated a quarter turn and to lie parallel with the side piece of the supporting frame, as shown in Fig. 1, where it 85 is held and prevented from shifting, until removed by the operator.

The arrangement of the parts in a trunk in the manner described permits a large supporting frame to be employed capable of 90 holding a large number of garments which may be projected to afford convenient access to them, to facilitate the operation of either packing or unpacking the garments.

By projecting the garment supporting 95 frame outwardly beyond the edge of the trunk body and into the cover the increased depth of the frame affords a large space in which the garments may be distributed and the ends of the guides 10 which also project 100 beyond the edge of the trunk body increases their bearing surfaces on the frame and as these also extend into the corners of the door or cover they serve as braces to strengthen the trunk.

We claim as our invention:

1. The combination with a trunk body having an open side and a supporting frame movable outwardly therefrom, of a strut, connections between the latter and the frame permitting said strut to be moved lengthwise in a direction transversely of the frame to project its lower end into engagement with the floor in front of the trunk to support the frame when the latter is adjusted outwardly 115 therefrom.

2. The combination with a trunk body having an open side and a supporting frame movably mounted therein, of a strut fitting within the body, means loosely connecting 120 the strut to the frame which causes the former to be carried on the latter and permits the strut to be adjusted laterally on the frame and projected bodily in a lengthwise direction relatively thereto into engagement 125 with the floor when the frame is moved outwardly.

3. The combination with a trunk comprising a body having an open side and a supporting frame movably mounted therein, of a 130

guide on the frame having its inner end elevated above its outer end and a strut traveling on said guide and adapted to engage the floor when at the lower end thereof.

5. The combination with a trunk comprising a body having an open side and a supporting frame movably mounted therein, of a guide having its forward end extending beneath the frame and its other end projecting rearwardly and upwardly above the bottom of the frame and a strut traveling on said guide.

10. The combination with a trunk comprising a body having an open side and a supporting frame movably mounted therein, of a guide attached to the frame having its outer end arranged below the frame and its inner end elevated above the bottom thereof and a strut depending from said guide and of a 15 length to engage the floor when the strut is moved onto the outer end of the guide.

15. The combination with a trunk comprising a body having an open side and a supporting frame movably mounted therein, of a strut adapted to project from a point beneath the frame into engagement with the floor and a guide supporting its upper end and connecting it to the frame, said guide having an upwardly extending portion which is adapted, when the strut is moved thereon, to elevate its lower end above the bottom of the 20 trunk.

25. The combination with a trunk comprising a body having an open side and a supporting frame movably mounted therein comprising side pieces and a connecting cross piece, of a guide having one end extending beneath the cross piece and attached thereto and its other end extending upwardly and 30 rearwardly and connected to one of the side pieces and a strut supported on the guide.

35. The combination with a trunk comprising a body having an open side and a supporting frame movably mounted therein

comprising side pieces and a connecting cross 45 piece, of a guide having one end secured to the cross piece and extending laterally beneath it and having its other end projecting rearwardly and upwardly and attached to one of the side pieces and a strut having an 50 eye surrounding the guide and movable thereon.

40. In a trunk, the combination with a body adapted to rest upon one of its ends and having an open side and a frame movably supported therein, of a strut extending upwardly from the floor and a guide connecting it to the frame, on which the strut is movable, having a portion adapted to elevate the strut above the bottom of the body and a 55 part which will move it into engagement with said bottom.

45. In a trunk, the combination with a body adapted to rest upon one of its ends and having an open side and a frame movably 60 supported therein, of a strut extending upwardly from the floor and a guide connecting it to the frame having a rearwardly extending end located at one side of the frame adapted to elevate the strut above the bottom of the body and provided with a laterally and downwardly extending part for subsequently moving it into engagement with 65 said bottom.

50. The combination with a trunk body 70 and a garment supporting frame movable inwardly and outwardly therefrom, of a supporting strut fitting within the body at one side of the frame when the latter is in its inward position, means connecting the strut to 75 the frame which permits it to be moved to a central point at the front of the frame when the latter is moved outwardly.
